STIRRING APPARATUS DRIVE WHEEL

Myron J. Zimmer, Wood Dale, Ill., assignor to
Eko Products Company, Chicago, Ill., a corpora-
tion of Illinois

Application October 12, 1946, Serial No. 133,909

Term of patent 3½ years

(Cl. D44—29)

To all whom it may concern:

Be it known that I, Myron J. Zimmer, a citizen of the United States, residing at Wood Dale, in the county of Du Page and State of Illinois, have invented a new, original, and ornamental Design for a Stirring Apparatus Drive Wheel, of which the following is a specification, reference being had to the accompanying drawing, forming part thereof.

Fig. 1 is a side elevational view of a stirring apparatus drive wheel, showing my new design.
Fig. 2 is a sectional view on line 2—2 of Fig. 1.
Fig. 3 is an edge elevational view thereof.

I claim:

The ornamental design for a stirring appara-
tus drive wheel, as shown.
